HINGE

Benjamin Shwayder, Detroit, Mich., assignor to
Schwayder Brothers, Inc., Denver, Colo., a corporation of Colorado

Application November 2, 1945, Serial No. 626,247

1 Claim. (Cl. 16—169)

1

This invention relates to a hinge construction, and more particularly to a hinge having a novel securing axis for the two relatively movable members pivotally mounted on said axis.

It is the object of this invention to provide a hinge characterized by an axis member having means associated therewith for maintaining the same in a fixed position relatively to the pivotal hinge members.

It is the object of this invention to provide a hinge with a pivot pin therefor carrying means for maintaining a fixed position thereof relative to the hinge members pivotally mounted thereon.

It is the further object of this invention to teach a new method of assembling hinges which consists of positioning the pivot pin relatively to and upon the extensions of the oppositely arranged hinge members, and oppositely forming said extensions around said pivot pin to pivotally join the same.

It is the further object of this invention to make said hinge particularly adaptable for use on luggage by providing punched-out portions or projections on the hinge members adapted to act as luggage supports.

These and other objects will be seen from the following specification and claims in conjunction with the appended drawing, of which

Fig. 1 is a perspective view of the hinge mounted upon a piece of luggage fragmentarily shown;

Fig. 2 is a broken-away elevational view of the hinge in its initial assembly step before forming of the hinge extensions; and

Fig. 3 is an enlarged fragmentary right-side elevational view thereof, with said extensions partially formed around their common pivot pin.

It will be understood that the above drawing illustrates merely a preferable embodiment of the invention, and that other embodiments are contemplated within the scope of the claim herein-after set out.

Referring to the drawing, the hinge comprises the two oppositely arranged hinge members 11 and 12, with common pivot 13. For example, said hinge is adapted for attachment to the piece of luggage 14, 15 fragmentarily shown in Fig. 1, by screws, studs, or rivets 16 which extend through the corresponding openings 17 formed within said hinge members.

Each hinge member 11 and 12 has a formed or punched outwardly projecting leg member 18 substantially hemispherical in form, which is adapted to act as a protecting support for the luggage when the hinged portions thereof are

2

resting on their corresponding longitudinal edges.

It is understood that two or more such hinges 11, 12 are secured to pivotal luggage members 14 and 15 whereby a four or more point support is provided maintaining the luggage off the ground, floor or other support.

Heretofore said leg members were separately mounted upon luggage and maintained thereon by rivets requiring unnecessary additional assembling operations which are now eliminated in the present construction. Furthermore, said leg members heretofore separately mounted, were likely to be torn off the luggage, or the rivets supporting the same were likely to be projected up into said luggage; in either case damaging the same.

As illustrated in Figs. 1 and 2, pivot pin 13 has a central annular flange 19 which is loosely retained against longitudinal movement within the opposed slots 20 in members 11 and 12.

Hinge member 11, Fig. 2, with continuous formed reinforcing ledge 21, has a pair of spaced extensions 22, which in the initial assembly step are flat. Hinge member 12, which is identical in shape with hinge member 11, also has a pair of corresponding spaced extensions 23. Member 12 when positioned as shown in Fig. 2, is adapted for associated nesting relation with hinge member 11 as shown.

It will be noted that the space between the two extensions of one hinge member is adapted to loosely receive the central extension of the other. For the initial assembly stage, hinge members 11 and 12 are oppositely positioned flat with their respective extensions 22 and 23 interlocked as shown in Fig. 2. Pivot pin 13 is then positioned upon said extensions with its annularly flanged portion 19 nesting within the two corresponding slots 20 of said hinged members.

In the last step, in a single forming operation, members 22 are turned upwardly and around pin 13 in substantially a semi-circle from one side of said pin; and members 23 are likewise turned up and around pin 13 from its other side. Pin 13 is fully enclosed now by formed members 22 and 23, while annular flange 19 is permanently retained within the corresponding slots 20 of members 11 and 12, as shown in Fig. 1.

Fig. 3 illustrates extensions 22 and 23 partially formed around pivot pin 13. Members 22 and 23 are formed oppositely until each member is bent around approximately 180 degrees for securing pivot pin 13 in position, but at the same time permitting relative pivotal movement of said hinge member 11 with respect to hinge member 12.

It will be noted from this construction that hinge members 11 and 12 are permanently associated relative to each other, and join around their common pivot pin 13.

It will be noted further that said pivot pin is permanently retained in its assembled position, and is prevented from relative transverse movement by means of its annular flange 19 seated within corresponding notches 20 in said hinge members.

It will be understood that the upsetting of the pin to form annular flanges 19 of the hinge pivot pins 13 may be done cheaply and in mass production.

By employing annular flange 19 it is seen that the hinge pin cannot be removed without destruction of the hinge itself. Heretofore, with the old type hinge, it was a relatively simple matter to knock out and remove the hinge pin providing access to an otherwise locked article or piece of luggage. In the present construction, once the hinge is assembled, the pivot pin is in place permanently and cannot be removed without destroying the hinge itself.

It will be noted further that in the present construction, peening of the ends of the pivot pin for locking the same within the hinge is eliminated inasmuch as said pin is retained in place by its annular flange or upset portion heretofore described in detail.

The annular flange 19 on pin 13 is preferably formed in a rivet header machine. However instead of applying pressure to the ends of the pin, inwardly directed pressure is applied by a pair of gripping members to portions of the pin adjacent its central portion flowing the metal inwardly to form annular flange 19. Said flange may also be formed in a punch press using dies with oppositely arranged receiving holes, with said holes of a length short of one half of the length of the

pin, so that when the dies are brought together the annular flange 19 will be formed.

Having described my invention, reference should now be had to the claim which follows for determining the scope thereof.

I claim:

A hinge comprising a pair of relatively pivotal hinge members with their common formed looped portions aligned in interlocked relation, a pivot pin transversely extending through said looped portions interconnecting said members, an annular flange intermediate the ends of said pin and integral therewith permanently retained against relative axial movement between an adjacent pair of said looped portions, and hemispherical legs adjacent the outer ends of said members, remote from said pivot pin, pressed outwardly therefrom and forming an integral part thereof for spacing said hinge above a supporting surface when its members are in alignment.

BENJAMIN SHWAYDER.
